UNITED STATES PATENT OFFICE.

ARTHUR LACHMAN, OF BERKELEY, CALIFORNIA, ASSIGNOR TO RICHFIELD OIL COMPANY OF CALIFORNIA, OF SAN FRANCISCO, CALIFORNIA, A CORPORATION OF DELAWARE.

METHOD OF REFINING MINERAL OILS.

Application filed December 8, 1926. Serial No. 153,249.

This invention relates to a method of purifying and refining mineral oils obtained by distilling or cracking, such as lubricating oils, kerosene, gasoline, shale oils, etc. The 5 method of refining mineral oils as described in this application is applicable to all mineral oils such as lubricating oils, kerosene, gasoline and shale oils, etc., and is particularly adaptable to oils obtained by a cracking process. For the purpose of simplifying the 10 description, reference will be made to gasoline only.

Crude gasoline is usually obtained by distillation or by cracking of crude petroleum and 15 consists of a mixture of saturated and unsaturated hydro-carbons, together with asphaltic materials, sulphur compounds, nitrogen bases and other substances of an undefined nature. These latter substances are 20 readily oxidizable at ordinary temperatures and are responsible for the color changes which take place when refined gasoline is stored. These oxidizable substances are 25 removed with difficulty when gasoline is refined by the methods now in common use.

In order to show the nature of my invention, it is desirable to describe the methods now in common use in oil refineries, and particularly that step of gasoline refining which 30 consists in de-odorizing and stabilizing the same. Crude gasoline obtained from the stills or cracking retorts, after condensation is treated with approximately 6 to 8 per cent by weight of sulphuric acid according to the 35 nature of the crude gasoline. The treatment usually consists in agitating the mixture of gasoline and sulphuric acid for an hour or more and then permitting it to settle, after which sulphuric acid sludge is withdrawn and the gasoline is washed with a 40 solution of alkali and finally with water. This treatment removes most of the impurities, but a subsequent treatment is frequently necessary in order to complete the de-odorization. 45 For this purpose a solution of sodium plumbite is commonly employed. The general objections to a treatment of this character are as follows:—1st: Gasoline purified by this method is frequently subject to discoloration 50 upon storage. Secondly, considerable quantities of sulphuric acid are required which are difficult to recover. Third: as much as ten per cent of the valuable hydrocarbons contained in the crude gasoline may be lost. 55 Fourth: The treatment must frequently be

followed with a deodorizing process such as that described.

My invention consists in the discovery that the sulphuric acid normally used in refining crude gasoline may be replaced with phosphoric acid and that gasoline treated with phosphoric acid and in some instances subsequently with a small amount of sulphuric acid or sodium hypo-chlorite will be water-white; stable as to color upon exposure to the 60 air and will, furthermore, require smaller amounts of acid and will reduce crude gasoline losses to a maximum of less than 2%.

The process briefly stated consists in treating gasoline or other volatile hydro-carbons 65 by passing the same while in a vapor state through or in contact with a body of phosphoric acid to remove nearly all of its impurities and subsequently completing the refining operation by condensing the vapor and 70 then treating it with a small percentage of sulphuric acid but preferably by washing it with a strongly alkaline solution of sodium hypo-chlorite. For the purpose of describing the process in more detail, reference will 75 be made to the accompanying drawings, 80 which is a diagrammatic view of one form of apparatus which may be employed.

Referring to this drawing, A indicates a cracking retort or the like from which the 85 crude gasoline vapors discharge through the pipe line 2. B indicates a tower of suitable 90 height and diameter filled with a resistant material, such as firebrick or the like indicated at 3 which forms numerous tortuous 95 passages through the tower. Disposed above the tower or adjacent to the same is a tank containing phosphoric acid preferably commercial acid of approximately 85% strength. This tank is connected with the top of the 100 tower by means of a pipe 4 having a regulating valve 5. This pipe terminates over a spreader plate 6 and this plate evenly distributes the acid when the valve 5 is opened over the brickwork or resistant material. The acid then flows downward through this 105 material and may finally be discharged through the bottom by a pipe 7, after which it is treated for recovery. The tower is also provided with a steam or water inlet pipe 8 which intermittently or continuously supplies a predetermined amount of water to the acid. The vapor from the still or cracking retort A enters the lower end of the tower at 110 a point 9. It passes up through the numer-

ous tortuous passages in the brickwork and comes into intimate contact with the phosphoric acid travelling or flowing over the same. Both acid and vapor are maintained at a temperature at from 160 to 200° C., and the vapor discharges at the upper end of the tower through a pipe 10 which is connected with a condenser 11 of suitable construction. The gasoline vapor entering at the temperature specified liberates and carries away a certain amount of water and the purpose of the steam or water inlet pipe 8 is that of continuously maintaining the acid at a certain water content so as to maintain the fluidity which is essential for good contact between the rising gas and the downflowing acid liquor. This completes the first step or treatment of the refining of crude gasoline by my process. During this treatment the major portion of the impurities are removed and carried out with the phosphoric acid as a sludge.

This treatment is, however, not sufficient and the condensed gasoline obtained is not commercially usable due to the presence of some odorous and gummy materials, as well as to its water content and further treatment is, accordingly, necessary. The condensate is conducted to a settling tank 12 where the water is allowed to deposit and is withdrawn. The gasoline is then agitated for a few minutes with a strongly alkaline solution of sodium hypo-chlorite. This removes the odorous and gummy constituents which have escaped the action of the phosphoric acid. After agitation for a few minutes the mixture is again allowed to settle, the alkaline sludge is withdrawn and the gasoline is now ready for use, requiring only occasionally a slight filtration to remove any suspended alkaline sludge. It is essential that the solution of sodium hydroxide employed for this purpose be strongly alkaline and carry a relatively high content of sodium hypo-chlorite.

As an example of the proportions of the materials required for the above described process for 100 pounds of gasoline approximately three pounds of phosphoric acid will be required during the first step of the refining operation. The strength of the phosphoric acid is the ordinary commercial strength of 85% but this may be varied within reasonable limits. The temperature at which the process is carried out will of itself determine the concentration of the acid but the concentration of the acid may be controlled by regulating the quantity of water or water vapor admitted. From 98 to 99 pounds of water-white gasoline will be obtained by this step which is separated from the water which distills over with it, which will be 2 to 3 pounds, as the process is normally carried out. The gasoline is now separated from the water and is thereupon agi-

tated with a solution of one-quarter pound of sodium hydroxide and one eighth of a pound of sodium hypo-chlorite dissolved in one pound of water. This agitation with the alkaline sodium hypo-chlorite solution should be carried out at ordinary room temperature if necessary with the aid of outside cooling. The agitation requires only from five to ten minutes. The gasoline loss through this operation is less than one-quarter pound. The gasoline may thereupon be stored for future use or filtered if required for prompt service.

Summing up the two steps of the operation, it will be noted that an exceedingly small amount of acid is required when comparison is made with the common sulphuric acid treatment in the manner described. Furthermore, the total loss of gasoline is reduced to a substantial amount of less than 2% of the total quantity treated. The sodium-hypo-chlorite is not recoverable but the phosphoric acid as well as the sodium hydroxide may be recovered and will be the subject of separate applications.

Having thus described my invention, what I claim and desire to secure by Letters Patent is:

1. A method of refining mineral oils which consists in heating the oil to form a vapor, passing the heated vapor through or in contact with a body of phosphoric acid maintained under high concentration, maintaining the acid at such concentration by the continuous addition of water and condensing the vapor after passing through the fluid acid.

2. A method of refining mineral oils, which consists in heating the oil to form a vapor at a temperature of approximately 160 to 200° C., passing the heated vapor through or in contact with a body of phosphoric acid maintained at a similar temperature and having a concentration of approximately 85%, maintaining the concentration of the acid substantially constant by the addition of water and finally condensing the vapor after passage through the acid.

3. A method of refining mineral oils which consists in heating the oil to form a vapor, passing the heated vapor through or in contact with a body of phosphoric acid and then condensing the vapor, and treating the condensate with a solution containing 18% sodium hydroxide and 9% sodium hypochlorite.

4. A method of refining mineral oils which consists in heating the oil to form a vapor, passing the heated vapor through or in contact with a body of phosphoric acid, maintaining the acid in a fluid condition by an addition of water and condensing the vapor after passing through the fluid acid, and treating the condensate with a strongly alkaline solution of hypo-chlorite.

ARTHUR LACHMAN.
